SCAFFOLD

Carl C. Droege, Greenfield, and Eugene J. Meloy
and William Clark Roggie, Indianapolis, Ind.,
assignors to Baker-Roos, Inc., Indianapolis,
Ind., a corporation of Indiana

Application December 27, 1946, Serial No. 718,716

3 Claims. (Cl. 304—3)

1

Our invention constitutes an improvement on the scaffold disclosed in the prior United States Letters Patent No. 2,335,046 to Carl C. Droege. The scaffold unit disclosed in that Droege patent is of the knock-down type and comprises a pair of vertical, ladder-like end frames which are held in parallel spaced relation by a horizontal bracing structure serving as a support for a platform, the bracing structure being adjustable on the end frames to support the platform at various elevations.

It is an object of the present invention to improve the construction of the Droege scaffold-unit and to simplify and lessen the cost of its manufacture. A further object of the invention is to increase the flexibility of the unit by adapting a plurality of units for superposition one on the other and by providing for the rigid interconnection of laterally spaced units. Still another object of the invention is to prevent accidental disassembly of each scaffold unit such as might result from a reversal of load.

In carrying out our invention, we form the end frames of each scaffold unit as ladders having parallel, vertically extending uprights; and we provide such uprights at their ends with provisions by which the end frames of a plurality of scaffold units may be supported one on the other and held in proper condition of alignment. The ladder-interconnecting structure of each unit comprises a pair of horizontal side rails each having at its ends provisions by which it may be releasably connected to corresponding uprights of the end frames of the unit. The uprights of each end frame are arranged to receive both side rails which are normal to the plane of the end frame and other rails which are coplanar with the end frame, so that such other rails may be used to interconnect a pair of laterally spaced scaffold units.

The accompanying drawings illustrate our invention:

Fig. 1 is a perspective view of an assembly of scaffold units; Fig. 2 is a fragmental side elevation of the scaffolding; Fig. 2a is a horizontal section on the line 2a—2a of Fig. 2; Fig. 3 is a vertical section on the line 3—3 of Fig. 2; Fig. 4 is a fragmental vertical section of the joint between uprights of superposed scaffold units; Fig. 5 is a vertical section through the lower end of the lowermost unit; Fig. 6 is a horizontal section on the line 6—6 of Fig. 5; Fig. 7 is a perspective view showing an assembly of scaffold units of modified construction; Fig. 8 is a side elevation in partial section of the scaffold unit illustrated in

Fig. 7; and Fig. 9 is a horizontal section on the line 9—9 of Fig. 8.

In the construction illustrated in Figs. 1 to 6, each scaffold unit comprises a pair of end frames 15 in the form of ladders having vertical uprights 15 interconnected by vertically spaced, horizontally extending rungs 16. Each side member 15 is conveniently formed of sheet-metal bent along parallel lines into a generally square, hollow cross-section, the edges of the metal, which either abut as shown at 17 in Fig. 2a or overlap as indicated at 17' in Fig. 6, being secured together as by welding. The rungs 16 may be metal rods, tubing, or pipe of circular cross-section and are permanently connected, as by welding, to the two side members 15 of the end frame.

In addition to two of the end frames 15—16, each of the scaffold units includes a pair of side rails 20 to the ends of which are secured shoes or guides 21. The guides 21 extend normally to the associated side rail 20, and the structure is desirably stiffened by obliquely extending brace members 22. Conveniently, the side rails 20, guides 21, and braces 22 are secured in assembled condition by welding. Each guide 21 comprises a pair of perpendicular flanges 23 and 24 adapted to engage two adjacent side faces of one of the vertical uprights 15 of an end element.

For the purpose of providing for the interconnection of side rails to the end frames at various elevations, the outer wall of each upright 15 is provided with a series of equally spaced openings 25, and the overlying flange 24 of each guide 21 is provided with a pair of vertically spaced lugs 26 adapted to be received respectively in two of the openings 25. In the arrangement shown in Figs. 1 to 6, it is contemplated that the openings 25 will be generally rectangular in form and that each lug 26 will be provided with a downwardly projecting head 27 having an outwardly presented, inclined face 28. The openings 25 are large enough to receive the heads 27; and after the heads have cleared the openings, the side rail may be lowered to bring the shanks of the lugs 26 into engagement with the lower edges of the holes 25, in which position the heads 27 will hold the uprights 15 seated in the guides 21.

Each of the side rails 20 is desirably L-shaped in cross-section to provide an inwardly extending flange 30 and an upwardly extending flange 30'. A platform 31 rests on the flanges 30 of opposed side rails, being confined laterally by the vertical flanges 30' of such side rails 20 and longitudinally by the flanges 23 of the guide members 21. Preferably, the platform 31 fits closely between the

vertical flanges 30' of the side rails 20 in order to stiffen the scaffold unit in a horizontal plane.

It will be evident from the construction described that the side rails 20 may be attached to a pair of end frames at any elevation permitted by the openings 25, thus permitting variation in the height of the platform 31. Downwardly directed loads applied to the platform are transmitted to the vertically extending uprights 15 through the lower faces of the lugs 26 and the lower ends of the openings 25. Thus, such loads tend to maintain the lug seated against the lower ends of the openings 25, in which position the heads 27 prevent separation of the end frames from the guides 21. Under certain conditions, however, as when an out-board load of sufficient magnitude is applied to one of the end frames, the unit may tend to tilt about the bottom of such end frame to raise the other end frame from the floor. Under such circumstances, the force of gravity acting on the elevated end frame would tend to cause it to move downwardly in its associated guide 21 to bring the openings 25 into a position such that the heads 27 of the lugs 26 could pass through them, and the elevated end frame might thus become separated from the associated side rails. To prevent any such separation upon a reversal of load, we employ releasable means capable of holding each end frame and its associated side rails in fixed relative position with the lug-heads 27 engaging the inner surface of the side wall of the upright 15. In the construction shown in the drawings, such means takes the form of a leaf spring 35 which is secured at one end to the guide-flange 24 and which is provided adjacent its other or free end with a projection 36 positioned to enter one of the openings 25 when the lugs 26 are seated in the position shown in Fig. 3. Normally, the leaf spring 35 lies parallel to the guide-flange 24, resiliently holding the projection 36 inwardly in such position that it may engage the upper end of the opening 25 in which it is received and limit relative upward movement of the guide 21 to an extent sufficient to prevent disengagement of the lug-heads 27. When it is desired to disassemble a unit, the free end of the leaf spring 35 is forced outwardly toward the dotted-line position shown in Fig. 3 to withdraw the projection 36 from the opening 25 and permit such upward movement of the side rail and guide 21 as is necessary to bring the heads 27 into alignment with the openings 25, whereupon the side rail may be removed from the end frame.

Each of the uprights is provided at one end with a socket or bushing 40 and at the other end with an outwardly projecting dowel pin 41 adapted to be received in the bushing 40 of another upright. Desirably, the bushings 40 are located at the lower ends of the uprights 15 and the pins 41 at the upper ends in order that the bushings may, when desired, be employed to receive the shanks 42 of casters 42'. By employing the interfitting pins 41 and bushings 40 to align superposed end frames a vertically extending series of scaffold units may be erected, as indicated in Fig. 1.

As will be obvious, in order for the lugs 26 to enter any pair of spaced holes 25 and hold the platform 30 at any desired elevation it will be necessary for the distance between the lugs to be an integral multiple of the distance between adjacent holes 25. By locating the end holes 25 in each upright 15 so that the sum of the dis-

tances between them and the respectively adjacent ends of the uprights will be an integral multiple of the hole-spacing, any side rail 20 may be placed at such an elevation that its associated guide 21 will overlap two superposed end frames with the upper lug 26 received in an opening 25 of one upright and the lower lug received in an opening 25 of the subjacent upright, as indicated in Fig. 3. In this manner, the joint between superposed uprights may be stiffened and an assembly of superposed scaffold units strengthened.

By providing a second series of openings 25' (Fig. 1) similar to the openings 25 but located in a tube-wall perpendicular to that in which the openings 25 are located, tie-rails 20' may be employed to interconnect laterally spaced scaffold units in the manner indicated in Fig. 1. The tie rails 20' are generally similar to the cross rails 20 and are provided with upright-engaging guides 21' having lugs, like the lugs 26, receivable in the openings 25'. By employing a series of laterally spaced scaffold units interconnected by tie rails 20', and by superposing tiers of similarly interconnected scaffold units, a rigid scaffold of adequate strength and stability can be erected to a great height.

In the modified form of the invention illustrated in Figs. 7, 8, and 9, the uprights 115 of the end frames are made of circular tubing or pipe instead of being made from sheet-metal as in the construction above described. Like the uprights 15, the uprights 115 are provided with a series of vertically spaced openings 125 adapted to receive lugs 126 on guides 121 which are secured to the ends of side rails 120 and braced by braces 122. In this instance, however, the openings 125 are of key-hole shape with their large ends at the top, and the lugs 126 are provided with circular heads 127 which are adapted to enter the larger ends of the openings 125 but which are too large to be removed through the smaller, lower ends of such openings. As a result, the normal downward load applied to the side rails will tend to keep the lugs seated in the position which locks the upright 115 to the guide 121. A leaf spring 135, provided with a projection 136, may be employed to prevent such upward movement of the side rail as would be necessary to free the lugs 126 from the openings 125.

If desired, each of the uprights 115 may be provided with two or more series of openings 125 spaced in planes located 90° apart about the axis of the upright. By utilizing tie rails 120' cooperating with a second set of openings 125, laterally spaced scaffold units may be interconnected in the same manner as that indicated in Fig. 1. As will be clear from Fig. 9, the guides 121 may have an angular extent of less than 90°, thus making it possible to locate both side and tie rails 120 and 120' at the same elevation.

Instead of employing tie rails 120' to interconnect directly two laterally spaced scaffold units, as the tie rails 20' are used in Fig. 1, the scaffolding may be extended horizontally by interconnecting a unit, or a vertical column of units, with single uprights 215 or with columns of such uprights. Where a still greater horizontal extent is desired, uprights 215 may be interposed between two horizontally spaced units, as indicated in Fig. 7, and connected to the end frames of both such units by tie rails 120'. Where single uprights 215 are used, they are desirably interconnected by side rails 120. If the side rails

120 and the tie rails 120' are of inverted T-section, as shown in Fig. 9, the platform within a scaffold unit can be extended by additional platform-sections 131 supported on the flanges of the tie rails 120'.

The rungs 16 of the end frames serve not only to interconnect the two uprights, 15 or 115, of such end frame but also provide a means enabling ascent to an elevated platform. The rungs 16 of each end frame are equally spaced to facilitate their use as a means of ascent; and to maintain uniform rung-spacing between superposed end frames, the sum of the distances between the end rungs and the respectively adjacent ends of the end frames is equal to the spacing between adjacent rungs within the end frame.

While we have shown the end frames in the drawings as of uniform length, it is to be understood that end frames of different lengths may be provided and may be incorporated in a single scaffold. End frames of relatively short length may be used where a roof or ceiling would prevent the use of end frames of normal length at the top of a column of units. Short end frames may also be used to support a side rail 20 or 120 at such an elevation above the platform 131 that it will serve as a guard to protect a workman on the platform against falling therefrom.

We claim as our invention:

1. In knock-down scaffolding, a plurality of end frames each including a pair of spaced uprights rigidly interconnected by a plurality of spaced horizontal rungs, said uprights being provided at their ends with complementary provisions adapted to interfit when two end frames are superposed and to hold the superposed end frames in alignment, horizontal side rails for interconnecting the uprights of opposed end frames, each of said side rails being provided at its ends with vertically extending guides adapted to receive the uprights of different end frames, each of said uprights being provided with a vertical series of equally spaced openings, each of said guides having a pair of vertically spaced lugs adapted to be received in interlocking relationship in two of said openings to prevent separation of the guide from its associated upright, the sum of the respective distances between end openings of the series and the adjacent ends of the upright being equal to an integral multiple of the distance between adjacent openings, whereby the lugs on any guide can be received respectively in openings of superposed uprights.

2. In knock-down scaffolding, a plurality of end frames each including a pair of spaced uprights, means rigidly interconnecting the uprights of each end frame, said uprights being provided at their ends with complementary provisions adapted to interfit when two end frames are superposed and to hold the superposed end frames in alignment, horizontal side rails for interconnecting the uprights of opposed end frames, each of said side rails being provided at its ends with vertically extending guides adapted to receive the uprights of different end frames, each of said uprights being provided with a vertical series of equally spaced openings, each of said guides having a pair of vertically spaced lugs adapted to be received in interlocking relationship in two of said openings to prevent

separation of the guide from its associated upright, the sum of the respective distances between end openings of the series and the adjacent ends of the upright being equal to an integral multiple of the distance between adjacent openings, whereby the lugs on any guide can be received respectively in openings of superposed uprights.

3. A knock-down scaffold unit, comprising a pair of end frames each including two spaced tubular uprights of rectangular cross-section interconnected by a plurality of horizontal rungs, one wall of each upright being normal to said rungs and secured thereto, a pair of side rails extending between said end frames, each of said side rails having at its ends vertical guides removably receiving corresponding uprights of the two end frames, each of said guides having surfaces engaging different sides of the received upright, each of said uprights being provided with a first vertically extending series of equally spaced openings in the wall opposite that to which the rungs are secured and being provided in one of the other upright-walls with a second vertically extending series of equally spaced openings, each of said guides having a pair of vertically spaced, headed lugs adapted to be received in any of a plurality of pairs of the openings in said first series, tie rails similar to said cross rails and provided with lugs co-operating with the openings of said second series for interconnecting a pair of laterally spaced scaffold units, said openings and lugs being so shaped and arranged that the heads of the lugs may be inserted in two of the openings by movement normal to the upright and then engaged with the inner surface of the upright-wall by downward movement of the associated guide relative to the upright, the heads on said lugs when engaged with the inner surface of the upright-wall lying wholly within the tubular upright.
